UNITED STATES PATENT OFFICE.

ROBERT SAMUEL ROBERTS, OF NEW ORLEANS, LOUISIANA.

RAIL-CHAIR.

1,360,685.

Specification of Letters Patent. Patented Nov. 30, 1920.

Application filed November 28, 1919. Serial No. 341,074.

To all whom it may concern:

Be it known that I, ROBERT SAMUEL ROBERTS, a citizen of the United States, residing at New Orleans, in the parish of Orleans and State of Louisiana, have invented new and useful Improvements in Rail-Chairs, of which the following is a specification.

The present invention comprehends the provision of a rail chair designed to possess maximum strength and durability for supporting the weight of the rolling stock, and at the same time affords the desired yieldability.

More specifically stated, the chair forming the subject matter of my invention is made up of two sections which can be quickly and readily associated when fitted to the tie, the said sections having alined depressions forming a channel beneath the base of the rail, to provide for the desired yieldability of the rail while the chair is provided with ribs disposed beneath the base of the rail in vertical alinement with the web thereof to give the chair the requisite strength to support the weight of the rolling stock.

Another object of the invention resides in the provision of means whereby the bolts are relieved of undue strain under tendency of the rail to move laterally.

The nature and advantages of the invention will be better understood when the following detail description is taken in connection with the accompanying drawings, the invention residing in the construction, combination and arrangement of parts as claimed.

In the drawing forming part of this specification like numerals of reference indicate similar parts in the several views and wherein:

Figure 1 is a top plan view.

Fig. 2 is a side elevation.

Fig. 3 is a longitudinal sectional view taken on the line 3—3 of Fig. 1.

Fig. 4 is a transverse sectional view taken on the line 4—4 of Fig. 1.

Fig. 5 is a detail view of one of the attaching plates.

Fig. 6 is a detail view of one section of a chair.

Referring to the drawings in detail, 10 indicates the railroad tie of the ordinary well known construction which is embraced by

means of the chair forming the subject matter of my invention. The chair comprises two identically constructed sections 11 and 12 respectively which are substantially L-shaped in cross section to engage the sides of the tie 10 and rest upon the top thereof. 55 The depending portion 13 of each section is provided with openings through which suitable fastening elements are driven into the tie for holding the chair in position thereon. The meeting edges of the horizontal portions of the respective sections, are reduced and overlapped as indicated at 14. Each overlapped portion is provided with a tongue and groove 15 and 16 respectively which are associated when the sections are 60 overlapped in a manner disclosed in Fig. 4. The chair is of course preferably constructed from metal, and each section is provided with openings 17 through which the fastening bolts 18 are driven for securing the rail 65 upon the chair in a manner to be hereinafter more fully described. Each chair section is formed with central depressed portions 19, which when the sections are associated unit- 70 edly define a channel underlying the base of the rail as shown in Fig. 3. Each section is formed with a rib 19' disposed transversely and centrally of the depressed portion 18, these ribs being arranged in alinement when the sections are associated. The ribs 19 are 75 also disposed immediately beneath the base of the rail in vertical alinement with the web 20 thereof, so as to afford the chair maximum strength to support the weight of the rolling stock. It will be noted however, 80 that the opposite longitudinal edges of the base of the rail are disposed upon the chair at opposite sides of the channel and consequently the rail is permitted by reason of this construction to yield under the weight 85 of the rolling stock in a desired manner. Each section at opposite ends of the horizontally disposed portion is formed with a shoulder 22, these shoulders being spaced an appreciable distance from the channels 18. 90

Attaching plates 23 are employed for securing the rail upon the chair, each plate including a reduced portion to overlap the base of the rail, while the opposite longitudinal edge of each plate bears against the shoulders 22 of the chair sections. By reason 95 of this construction, the spikes 18 which pass through the openings 26 in the plate and also through the openings 17 in the chair, are 100 105

relieved of undue strain to any tendency of the rails to move laterally. This arrangement obviously adds to the general strength and durability of the chair in its entirety.

5 While it is believed that from the foregoing description the nature and advantages of the invention will be readily apparent, I desire to have it understood that I do not limit myself to the exact construction and 10 arrangement of parts disclosed and that such changes may be resorted to when desired as fall within the scope of what is claimed.

Having thus described my invention what I claim as new is:—

- 15 1. A rail chair comprising a pair of substantially L-shaped sections having their meeting edges overlapped, means for securing said sections to the tie, each section having a central depressed portion unitedly defining a channel disposed immediately beneath the base of the rail, and a rib arranged transversely of each section and centrally disposed with respect to the depressed portion for the purpose specified.
- 20 2. A rail chair comprising two substan-

tially L-shaped sections, having their adjacent edges reduced and overlapped, means for securing said sections to the tie, said overlapped edges of the respective sections having a tongue and groove connection, said sections having alined depressed portions underlying the base of the rail, and ribs arranged in said depressed portions to engage the base of the rail, in alinement with the web thereof for the purpose specified. 35

3. A rail chair comprising two substantially L-shaped sections, having their meeting edges overlapped, and means for securing said sections to the tie, shoulders formed at the ends of said sections, said shoulders being spaced from the adjacent edges of the base of the rail, attaching plates arranged upon said chair each having a portion overlying the base of the rail, bolts passed through said plates and chair for securing the rail to the tie, and the opposite edges of said plates bearing against said shoulders to relieve the bolts of undue strain as specified. 40 45

In testimony whereof I affix my signature.
ROBERT SAMUEL ROBERTS.
